(57) **CLAIM**

The ornamental design for a sliding tray, as shown and described.

DESCRIPTION

FIG. 1 is a first front perspective view of a sliding tray showing my design.

FIG. 2 is a bottom rear perspective view of the sliding tray.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings are employed to show unclaimed portions of the sliding tray, and form no part of the claimed design.

1 Claim, 8 Drawing Sheets**FIG. 1**

FIG. 2

FIG. 3

FIG. 4

FIG. 5

FIG. 6

FIG. 7

FIG. 8
